US0D1036193S

(12) **United States Design Patent** (10) Patent No.: **US D1,036,193 S**
(45) Date of Patent: ** Jul. 23, 2024

(54) **CONTAINER LID**

- (71) Applicant: **Cirkul, Inc.**, Tampa, FL (US)
- (72) Inventors: **Garrett S. Waggoner**, Tampa, FL (US);
Andrew J. Gay, Bothell, WA (US);
Thomas A. Urbanik, Maynard, MA (US); **Cole Houston**, Central Falls, RI (US); **Corey Jerolmon**, Boston, MA (US)
- (73) Assignee: **Cirkul, Inc.**, Tampa, FL (US)
- (**) Term: **15 Years**
- (21) Appl. No.: **29/760,048**
- (22) Filed: **Nov. 27, 2020**
- (51) LOC (14) Cl. **07-02**
- (52) U.S. Cl. **D7/392.1**
- (58) Field of Classification Search
USPC D7/300, 318, 392, 392.1, 510, 533, 538, D7/619.1, 629
CPC B65D 83/205; B65D 83/206; B65D 83/40; A47G 19/2272
